UNITED STATES PATENT OFFICE.

ALOIS ROSTAS, OF TRENTON, NEW JERSEY.

CARBURETOR-LOCK MECHANISM.

Application filed July 18, 1927. Serial No. 206,604.

This invention relates to certain new and useful improvements in carburetor lock mechanism and has for its primary object a lock mechanism for carburetors that operate to shut off the supply of gasoline to the carburetor to prevent unauthorized use of the automobile.

A further object of the invention is to provide a carburetor lock in which a rotatable cylinder supported within the float chamber has an opening therein registering with the communicating passage between the float and mixing chambers of the carburetor, the rotatable cylinder being manually operable for shutting off communication between the float and mixing chambers of the carburetor with lock mechanism for holding the cylinder in its adjusted position and operating the stem of the float valve for shutting off the supply of gasoline to the float chamber.

With the above and other objects in view that will become apparent as the nature of the invention is better understood, the same consists in the novel form, combination and arrangement of parts hereinafter more fully described, shown in the accompanying drawings and claimed.

In the accompanying drawings wherein like reference characters are employed to designate corresponding parts throughout the several views.

Figure 1 is a side elevational view of an automobile partly broken away and showing the carburetor lock mechanism associated with the carburetor, the lock mechanism being controlled from the instrument board of the automobile;

Figure 2 is a side elevational view of a carburetor, partly broken away and shown in section to illustrate the rotatable cylinder in the float chamber that is manually operable for closing communication between the float and mixing chambers of the carburetor;

Figure 3 is a detail sectional view taken on line 3-3 of Figure 2 showing the tensioned pins operated by the float mechanism in the float chamber for holding the rotatable cylinder in its adjusted position;

Figure 4 is a cross-sectional view taken on line 4-4 of Figure 3 showing the socket in the inner face of the float chamber wall with which openings in the rotatable cylinder are adapted to register for receiving the tensioned locking pins and with the float removed;

Figure 5 is a detail sectional view taken on

line 5-5 of Figure 2, showing the opening in the rotatable cylinder that forms communication between the float and mixing chambers;

Figure 6 is a fragmentary front elevational view of the instrument board of the automobile with the lock casing for the carburetor mounted thereon;

Figure 7 is a vertical cross-sectional view taken on line 7-7 of Figure 6 showing the lock tumbler mechanism that is bodily shiftable within the lock casing and detachably connected to the operating wire or rod associated with the needle valve in the float chamber;

Figure 8 is a cross-sectional view taken on line 8-8 of Figure 7;

Figure 9 is a cross-sectional view taken on line 9-9 of Figure 7 showing the rotatably tensioned tumblers and the device for connecting the lock mechanism to the operating member for the needle valve in the float chamber;

Figure 10 is a cross-sectional view taken on line 10-10 of Figure 9 showing the key within the lock mechanism and in position for shifting the lock tumblers;

Figure 11 is a longitudinal sectional view of the sleeve within the lock casing that encloses the lock mechanism;

Figure 12 is a cross-sectional view taken on line 12-12 of Figure 9 showing the spring catch for retaining the cover plate of the lock in position and the wire or rod that extends from the lock mechanism to the needle valve of the float chamber;

Figure 13 is a perspective view of the key for operating the lock mechanism; and

Figure 14 is a detail sectional view showing a tensioned rod interposed between the lock mechanism and the needle valve of the float chamber.

The object of this invention being the provision of lock mechanism associated with the carburetor of an automobile to shut off the supply of gasoline to the float chamber and also to shut off communication between the float and mixing chambers of the carburetor, there is illustrated in Figure 1 an automobile designated by the reference character A which is broken away to show the carburetor B, connecting devices being formed between the carburetor and the lock casing C upon the instrument board D, there being also illustrated in Figure 1, an operating member E for a part of the car-

buretor lock mechanism that extends between the carburetor and the instrument board.

As shown in Figure 2, the carburetor B 5 comprises a float chamber 1 and a mixing chamber 2 that communicate with each other by means of the passage 3 shown in Figure 5. The float chamber 1 is supplied with gasoline in the usual manner through the 10 bottom pipe connection 4, the chamber 1 containing the float 5 that is guided in its movement by the needle valve 6 with which the counter-balanced weights 7 are associated for lowering the needle valve 6 to its 15 closed position when the float 5 rises to operate the weights 7. As shown in Figures 2 to 5, a sleeve 8 is rotatably supported in the float chamber 1 in frictional contact with the inner face of the float chamber wall and 20 said sleeve has an opening 9 adjacent its lower end that registers with the passage 3 to furnish communication between the interior of the float chamber and the mixing chamber of the carburetor. The means for 25 rotating the sleeve 8 for moving the opening 9 therein into and out of communication with the passage 3 is shown more clearly in Figure 2 and comprises an arm 10 projecting laterally of the upper end of the sleeve 30 8 and extending through the inclined slot 11 formed in the upper edge of the float chamber wall and in the lower edge of the cover 12 for the float chamber, the inclined slot 11 causing the sleeve 8 when rotated to 35 also be moved downwardly to cause a binding action between the lower edge of the sleeve and the bottom wall of the float chamber when the opening 9 in the sleeve is displaced from the passage 3 to insure against 40 leakage of gasoline from the float chamber to the mixing chamber. The operating rod 45 E is pivotally connected at its lower end to the outer end of the arm 10 as at 13 while the upper end thereof that extends through the instrument board D, as shown in Figure 1, is provided with a handle or button 14.

Devices are associated with the sleeve 8 for holding the same in shifted position with communication between the float and mixing chambers shut off and such devices form a part of the lock mechanism to be later described, said lock mechanism being associated with the needle valve 6 for lowering the same upon its valve seat to shut off 55 the supply of gasoline to the float chamber. When the needle valve 6 is lowered to shut off the supply, the counter-balanced weights 7 are raised and act in the same manner as when operated by the float 5. As shown in 60 Figures 3 and 4, the hanger brackets 15 that depend from the float chamber cover 12 for pivotally supporting the counter-balanced weights 7, carry at each side thereof, a barrel 16 in which a pin 17 is slidably mounted and 65 spring pressed as at 18. A bail lever 19 is

pivotaly supported at 20 upon the spaced barrels 16 and in the path of movement of one of the counter-balanced weights 7, upward movement of said counter-balanced weights operating the bail lever 19 that is 70 moved into engagement with the tensioned pins 17 for projecting them through the barrels 16, and also through the openings 21 in the sleeve 8, which have been moved into alignment therewith, with the outer ends of 75 the tensioned pins 17 being received in recesses 22 in the form of sockets formed in the inner face of the float chamber wall. When the sleeve 8 is manually shifted by the pull rod E to destroy communication between the float and mixing chambers, the openings 21 in the sleeve are moved into 80 registration with the sockets 22 and into position to receive the spring pressed pins 17 for locking the sleeve in its adjusted 85 position.

The lock mechanism within the casing C that is associated with the operating device for the needle valve 6 is shown more clearly in Figures 6 to 14, the lock casing comprising a box structure 23 that is set into an opening in the instrument board D, the upper side of the box being open and provided with inwardly directed flanges 24 that are secured by fastening devices 25, the rectangular facing strip 26 that in turn is secured to the instrument board D by the fastening devices 27. A removable cover plate 28 is provided for the open side of the box of the lock casing and as shown in Figures 8 and 9 the cover plate 28 is provided adjacent one end thereof with a pair of clips 29 upon the inner face that engage the box flange 24 for retaining one end of the cover in position. The other end of the cover 28 carries a U-shaped strap 30 in which a spring pressed pin 31 is slidably mounted, said pin being retracted against spring tension thereon by the lever 32 in a manner to be later described. A sliding catch 32 guided in its 100 movement by the member 34 carried by the rectangular facing strip 26 as shown in Figures 6 and 12 is projected through a side opening in the box 23 with the apertured end thereof moved into position to receive the 105 spring pressed pin 31, the latch plate 33 being retained against accidental movement by the stud screw 35. With the latch plate 33 in the position shown in Figure 12, the cover 28 is retained in position and when 110 the lever 32 is operated to disengage the pin 31 from the latch plate 33, the latter is slid laterally away from the pin 31 to permit removal of the cover plate. The lock casing is further secured within the opening in the instrument board by the angle straps 36 attached to the end walls of the lock casing and the forward side of the instrument board. The cover plate 28 is provided with a central opening in which a key 115

hole guard 37 is slidably mounted, the enlarged outer ends of the key hole guard carrying a tubular portion 38 slidable through the opening in the cover plate and 5 being angularly flanged at its inner end in the form of a disk 39.

As shown in Figure 12, a pair of rods 40 are carried by the bottom wall of the lock casing 23 and extend into openings provided 10 therefor in the removable cover plate 28. Each shaft 40 is inclosed by a slidable sleeve 41 and said sleeves intermediate the ends thereof are formed integral with a disk plate 42. A central opening is formed in the bottom wall of the lock casing 23 and is surrounded by a metal pipe 43 that extends to the float chamber of the carburetor to inclose the upper end of the needle valve 6 that projects above the float chamber and to be 15 threaded through the cover of the float chamber as at 44. A wire rod 45 is inclosed by the pipe 43 and has a head 46 on its forward end for engagement with the needle valve, the upper end of the wire rod 45 being fixed to the collar 47 that has an annularly grooved head 48. The collar 47 is detachably connected to the sleeve 41 and disk plate 42 by the latch 49 that is engaged with the grooved head 48 intermediate its ends, 20 the latch 49 being pivotally supported at one end as at 50 upon one sleeve 41 with the other end 51 thereof moved into engagement with the other sleeve, see Figures 9 and 12.

Key operated lock mechanism within the 25 casing 23 is associated with the disk plate 42 and is intended for shifting the disk plate within the casing with the sleeve 47 carrying the operating rod 45 attached thereto by the latch 49. The lock mechanism comprises 30 a plurality of spacer disks 52 having openings therein to be received on the sleeves 41 that enclose the rods 40, the spacer disks 52 having alined peripheral notches 53 formed therein. One or more tumbler bars 54 are 35 spaced by the spacer disks 52 and are of a length slightly greater than the diameter of said disks, the several spacer disks 52 and the tumbler bars 54 having central openings 55 therein that are of configuration as shown in 40 Figure 8. One side edge of each tumbler bar 54 adjacent corresponding ends is provided with a notch 55^a that is engaged by the leg extension 57^a of the coil spring 57 that is secured to the bottom face of the disk plate 42, the spring tending to move the tumbler bars in one direction and to be limited by the 45 spring end 57^a engaging the abutment shoulders of the spacer disk notches 53. The spacer disks and tumbler bars are enclosed within the cylinder 56 shown in detail in Figure 11, the cylinder having longitudinally extending diametrically opposite slots 56^a and diametrically opposite threaded portions 58 in the inner wall of the cylinder 50 adjacent the grooves. The cylinder 56 has

an end flange 59 for attachment to the bottom wall of the lock casing 23 and to be retained in position by the fastening devices 60. The opposite end of the cylinder 56 has a cut away portion 61 to provide a clearance for the lever 32 that controls operation of the spring pressed pin 31 which retains the removable cover plate 28 in position, this arrangement being clearly shown in Figures 11 and 12. When the several spacer 70 disks 52 and tumbler bars 54 have been assembled in the proper manner, the cylinder 56 is then placed in position, the longitudinally extending grooves 56^a of the cylinder being alined with the projecting ends of the 75 tumbler bars 54 which permit the cylinder to be placed in enclosing relation with respect to the lock mechanism. When so disposed, the cylinder 56 is then rotated in the proper direction to move the projecting ends of the 80 tumbler bars 54 into the threaded portions of the cylinder and the latter is then secured to the bottom wall of the lock casing. When so arranged, the openings 55 in the spacer 85 disks and tumbler bars properly register to permit the insertion of the key for operating the tumbler bars.

The operating key for the locking mechanism is shown more clearly in Figures 10 and 13, the key comprising a rectangular shank 62 having spacer rings 63 mounted thereon for separating the tumbler key 64, the rings 63 and tumbler keys 64 being retained in position on the key shank 62 by the key head 65 that is threaded onto the outer end of the shank. The tumbler keys 64 are positioned on the key shank so that when the key is fully inserted in the lock mechanism through the openings 55 in the spacer disks 90 95 100 105 110 115 120 125 130 135 140 taints the ends of the tumbler bars 54 in the threaded portions 58 of the cylinder 56, the lock mechanism then being retained against shifting movement within the lock casing 5 and with the needle valve 6 locked upon its seat. When the tumbler bars 54 have their ends disposed in engagement with the threads 58, the several openings 55 in the spaced disks and tumbler bars are alined 10 with each other, which enables the positioning of the key through the several openings for the operation of the lock mechanism. To release the needle valve 6 from its seat, the key is inserted in the lock mechanism and 15 the key tumblers 64 are so disposed on the shank of the key to be received in the similarly formed openings 55 in the tumbler bars when the key is completely inserted in the lock mechanism. Upon turning the key 20 in the proper direction, the tumbler bars 54 are shifted against the tension of the spring 57 to dispose the ends thereof in the diametrically opposite slots 56^a in the cylinder 56, the key tumblers 64 being then disposed to 25 extend across the openings in the spacer disks 52 so that an outward pull upon the key will shift the spacer disks, tumbler bars, disk 42 and the sleeve 47 that is attached to the disk by the latch 49 to shift the rod 45 30 and displace the head 46 thereof from engagement with the upper end of the valve 6. When the lock mechanism has been moved toward the cover plate 28 of the lock casing, the key is rotated in the reverse direction to move the ends of the tumbler bars 35 54 into adjacent threads 58 of the cylinder 56, and when the tumbler bars are so disposed, all of the openings 55 in the spacer disks and tumbler bars are alined to permit 40 removal of the key. When the needle valve 6 is released from its seat, the counter-balanced weight 7 descends to retract the spring 45^a pressed pins 17 and permit manual shifting of the sleeve 8 to aline the opening therein 45 with the passage 3.

In the operation of the mechanism as shown in Figures 1 to 13 the rod 45 is positively moved in opposite directions into and out of engagement with the needle valve 6, while in Figure 14 which shows a modified form of construction, the head 46^a of the rod 45^a is spring pressed as at 66 which aids in the projection of the rod 45^a when the end thereof attached to the sleeve 47 is permitted 50 to be shifted toward the bottom wall of the lock casing when the lock mechanism is moved into releasing position.

From the above detailed description of the invention, it is believed that the construction and operation thereof will at once be understood, and while there are herein shown and described the preferred embodiments of the present invention, it is nevertheless to be understood that minor changes may be 60 made therein without departing from the

spirit and scope of the invention as claimed.

What I claim as new is:—

1. In carburetor lock mechanism of the type described, key-operated means for shutting off the supply of gasoline to the float chamber of the carburetor, and manually operable means for shutting off communication between the float and mixing chambers of the carburetor, the manually operable means including a sleeve in the float chamber having an opening therein movable into and out of registry with the passage forming communication with the mixing chamber. 70 75

2. In carburetor lock mechanism of the type described, key-operated means for shutting off the supply of gasoline to the float chamber of the carburetor, manually operable means for shutting off communication between the float and mixing chambers of the carburetor, and means operated by the key operated means for locking the manually operable means in shifted position, the manually operable means including a sleeve in the float chamber having an opening therein movable into and out of registry with the passage forming communication with the mixing chamber. 80 85 90

3. In carburetor lock mechanism of the type described, key-operated means for shutting off the supply of gasoline to the float chamber of the carburetor, manually operable means for shutting off communication between the float and mixing chambers of the carburetor, the manually operable means including a sleeve in the float chamber having an opening therein movable into and out of registry with the passage forming communication with the mixing chamber, an arm of the sleeve projecting outwardly of the float chamber, and a pull wire attached 95 100 105 to the arm.

4. In carburetor lock mechanism of the type described, key-operated means for shutting off the supply of gasoline to the float chamber of the carburetor, manually operable means for shutting off communication between the float and mixing chamber of the carburetor, means operated by the key operated means for locking the manually operable means in shifted position, the manually operable means including a sleeve in the float chamber having an opening therein movable into and out of registry with the passage forming communication with the mixing chamber, an arm on the sleeve projecting outwardly of the float chamber, and a pull wire attached to the arm. 110 115 120

5. In carburetor lock mechanism of the type described, key-operated means for shutting off the supply of gasoline to the float chamber of the carburetor, manually operable means for shutting off communication between the float and mixing chambers of the carburetor, the manually operable means including a sleeve in the float chamber 125 130

- ber having an opening therein movable into and out of registry with the passage forming communication with the mixing chamber, the means operated by the key-operated means comprising tensioned pins within the float chamber, said sleeve and float chamber having openings adapted to register when the sleeve is shifted to full shut-off position, and said pins being moved into said openings when the counter balance weights are raised upon forceful closing of the needle valve in the float chamber.
6. In carburetor lock mechanism of the type described, key-operated means for shutting off the supply of gasoline to the float chamber of the carburetor, manually operable means for shutting off communication between the float and mixing chambers of the carburetor, means operated by the key operated means for locking the manually operable means in shifted position, the manually operable means including a sleeve in the float chamber having an opening therein movable into and out of registry with the passage forming communication with the mixing chamber, the means operated by the key-operated means comprising tensioned pins within the float chamber, said sleeve and float chamber having openings adapted to register when the sleeve is shifted to full shut-off position, and said pins being moved into said openings when the counter-balance weights are raised upon forceful closing of the needle valve in the float chamber.
7. In carburetor lock mechanism of the type described, key-operated means for shutting off the supply of gasoline to the float chamber of the carburetor, manually operable means for shutting off communication between the float and mixing chambers of the carburetor, the manually operable means including a sleeve in the float chamber having an opening therein movable into and out of registry with the passage forming communication with the mixing chamber, an arm of the sleeve projecting outwardly of the float chamber, a pull wire attached to the arm, the means operated by the key-operated means comprising tensioned pins within the float chamber, said sleeve and float chamber having openings adapted to register when the sleeve is shifted to full shut-off position, and said pins being moved into said openings when the counter balance weights are raised upon forceful closing of the needle valve in the float chamber.
8. In carburetor lock mechanism of the type described, key-operated means for shutting off the supply of gasoline to the float chamber of the carburetor, manually operable means for shutting off communication between the float and mixing chamber of the carburetor, means operated by the key operated means for locking the manually operable means in shifted position, the man-
- ually operable means including a sleeve in the float chamber having an opening therein movable into and out of registry with the passage forming communication with the mixing chamber, an arm on the sleeve projecting outwardly of the float chamber, a pull wire attached to the arm, the means operated by the key-operated means comprising tensioned pins within the float chamber, said sleeve and float chamber having openings adapted to register when the sleeve is shifted to full shut-off position, and said pins being moved into said openings when the counter balance weights are raised upon forceful closing of the needle valve in the float chamber.
9. In carburetor lock mechanism of the type described, key-operated means for shutting off the supply of gasoline to the float chamber of the carburetor, manually operable means for shutting off communication between the float and mixing chambers of the carburetor, the key-operated means comprising lock mechanism, means between the needle valve of the float chamber and lock mechanism detachably connected to the lock mechanism, and said key moving the lock mechanism and the last named means to space the latter from the needle valve of the float chamber.
10. In carburetor lock mechanism of the type described, key-operated means for shutting off the supply of gasoline to the float chamber of the carburetor, manually operable means for shutting off communication between the float and mixing chambers of the carburetor, means operated by the key operated means for locking the manually operable means in shifted position, the key-operated means comprising lock mechanism, means between the needle valve of the float chamber and lock mechanism detachably connected to the lock mechanism, and said key moving the lock mechanism and the last named means to space the latter from the needle valve of the float chamber.
11. In carburetor lock mechanism of the type described, key-operated means for shutting off the supply of gasoline to the float chamber of the carburetor, manually operable means for shutting off communication between the float and mixing chambers of the carburetor, the key-operated means comprising lock mechanism, means between the needle valve of the float chamber and lock mechanism detachably connected to the lock mechanism, said key moving the lock mechanism and the last named means to space the latter from the needle valve of the float chamber, the lock mechanism comprising a fixed cylinder, a pair of rods extending through the cylinder, a plurality of spacer disks on the rods, a plurality of tumbler bars separated by the spacer disks and locked to the cylinder, said disks and tumbler bars

having similar openings centrally thereof, and a key having tumbler wards to be received in the opening in the tumbler bars for rotating the latter to displace them from engaged relation to the cylinder.

12. In carburetor lock mechanism of the type described, key-operated means for shutting off the supply of gasoline to the float chamber of the carburetor, manually operable means for shutting off communication between the float and mixing chambers of the carburetor, means operated by the key operated means for locking the manually operable means in shifted position, the key-operated means comprising lock mechanism, means between the needle valve of the float chamber and lock mechanism detachably connected to the lock mechanism, said key moving the lock mechanism and the last named means to space the latter from the needle valve of the float chamber, the lock mechanism comprising a fixed cylinder, a pair of rods extending through the cylinder, a plurality of spacer disks on the rods, a plurality of tumbler bars separated by the spacer disks and locked to the cylinder, said disks and tumbler bars having similar openings centrally thereof, and a key having tumbler wards to be received in the opening in the tumbler bars for rotating the latter to displace them from engaged relation to the cylinder.

13. In carburetor lock mechanism of the type described, key-operated means for shutting off the supply of gasoline to the float chamber of the carburetor, manually operable means for shutting off communication between the float and mixing chambers of the carburetor, the key-operated means comprising lock mechanism, means between the needle valve of the float chamber and lock mechanism detachably connected to the lock mechanism, said key moving the lock mechanism and the last named means to space the latter from the needle valve of the float chamber, the lock mechanism comprising a fixed cylinder, a pair of rods extending

through the cylinder, a plurality of spacer disks on the rods, a plurality of tumbler bars separated by the spacer disks and locked to the cylinder, said disks and tumbler bars having similar openings centrally thereof, a key having tumbler wards to be received in the opening in the tumbler bars for rotating the latter to displace them from engaged relation to the cylinder, and said cylinder having diametrically opposite longitudinally extending grooves into which the ends of the tumbler bars are moved to permit shifting of the lock mechanism.

14. In carburetor lock mechanism of the type described, key-operated means for shutting off the supply of gasoline to the float chamber of the carburetor, manually operable means for shutting off communication between the float and mixing chambers of the carburetor, means operated by the key operated means for locking the manually operable means in shifted position, the key-operated means comprising lock mechanism, means between the needle valve of the float chamber and lock mechanism detachably connected to the lock mechanism, said key moving the lock mechanism and the last named means to space the latter from the needle valve of the float chamber, the lock mechanism comprising a fixed cylinder, a pair of rods extending through the cylinder, a plurality of spacer disks on the rods, a plurality of tumbler bars separated by the spacer disks and locked to the cylinder, said disks and tumbler bars having similar openings centrally thereof, a key having tumbler wards to be received in the opening in the tumbler bars for rotating the latter to displace them from engaged relation to the cylinder, and said cylinder having diametrically opposite longitudinally extending grooves into which the ends of the tumbler bars are moved to permit shifting of the lock mechanism.

In testimony whereof I affix my signature.

ALOIS ROSTAS.
